UNITED STATES PATENT OFFICE.

JOSEPH E. KENNEDY, OF NEW YORK, N. Y.

DRIVING MECHANISM FOR CRUSHERS.

1,385,687.

Specification of Letters Patent. Patented July 26, 1921.

Original application filed October 23, 1917, Serial No. 198,023. Divided and this application filed January 12, 1918. Serial No. 211,634.

To all whom it may concern:

Be it known that I, JOSEPH E. KENNEDY, a citizen of the United States, and a resident of the borough of Manhattan, city, county, 5 and State of New York, have invented certain new and useful Improvements in Driving Mechanism for Crushers, of which the following is a specification.

The present application is a division of 10 that filed by me October 23, 1917, Serial No. 198,023, and relates more particularly to the means for driving the eccentric by which the gyratory shaft is operated. Gear driven mills are adapted to coarse reduction of 15 material, but the increased use of relatively finely crushed material for concrete and similar purposes has created a demand for apparatus adapted to produce a relatively large output of the finer graded material 20 more rapidly than heretofore. Hence, the main object of my invention is to speed up crushing apparatus of the gyratory type, and to otherwise adapt it to the special requirements for use in the production of 25 material of relatively fine grade,—the invention consisting in the specific construction and arrangement of parts described and claimed herein, a distinctive feature being the means employed for guiding and controlling the endless drive for the rotatable sleeve in which the eccentric bearing is 30 mounted, all as hereinafter fully set forth.

In the accompanying drawings,

Figure 1, is a plan of my improved crushing apparatus, with means for driving same;

Fig. 2, is a central vertical sectional elevation taken mainly upon plane of line 2—2, Fig. 1;

Fig. 3, is a rear elevation showing the 40 driving means;

Fig. 4, is a horizontal section taken upon plane of line 4—4, Fig. 2.

In general characteristics the apparatus illustrated in the drawings is primarily the same in principle and operation as set forth 45 in Letters Patent No. 1,085,867, issued to me Feb. 3, 1914, No. 1,090,216, issued to me March 17, 1914, and No. 1,176,833, issued to me March 26, 1916, to which reference may 50 be had as showing the type of gyratory crusher to which my present improvements are especially applicable. Thus the truncated conical crushing head a , is rigidly secured to the shaft A, and is gyrated thereby 55 within a concave crushing chamber b , from

the lower portion of which the reduced material drops into the chute chamber d , in the usual manner.

The shaft A, is suspended on an inclosed top or cover C, of special construction, having a central hub c , formed with an inturned bottom flange or annular shoulder c' , on which the said shaft A, is fulcrumed in such manner as to allow of its gyration by means of the eccentric bearing e , in which the lower end of said shaft A, is mounted. The upper extremity of the shaft A, is screw threaded and provided with a nut collar a' , which bears on a sleeve a^2 , resting in turn on a gasket a^3 , interposed between it and said annular shoulder c' , of the hub c , of the cap plate C, as shown particularly in Fig. 2,—a bushing c^2 , being interposed between the hub c , and the bearing sleeve a^2 .

To the upper part of this eccentric bearing sleeve e' , is rigidly secured, as by the key e^2 , the driven pulley e^x , by which said sleeve e' , is rotated to impart a gyratory rotation to the shaft A, through the medium of the aforesaid eccentric bearing e , the operation and functions of which latter are clearly set forth in the Letters Patent hereinbefore referred to, particularly Letters Patent No. 1,176,833.

The eccentric sleeve pulley e , is preferably grooved peripherally to receive one or more drive belts i , usually in the form of ropes which pass under deflecting idler pulleys I, (Fig. 3) to a driving pulley or rope sheave J, on the power shaft K. The journals of the idler pulleys or rope sheaves I, are mounted in bearings which may be regulated in inclination as well as vertically and horizontally so as to afford practically universal adjustment as related to the eccentric sleeve pulley e^x . By this means also taut and accurate service of the ropes or belt i , to the said pulley e^x , is attained,

so that the eccentric sleeve e' , may be rotated at a relatively high speed as compared 100 with the old method of driving it by miter gearing. Thus by my new method of gyratory drive the speed and capacity of the apparatus may be safely increased one hundred per cent. or more. The provision of the universally adjustable idlers I, also enables me to readily install the crushing apparatus at a much lower level than the available power, as is frequently necessary 105 in practice.

The belts i , i , pass through openings d' , d' , specially formed for them in the bottom shell D , which is otherwise continuous in horizontal cross section and incloses the driving pulley e^* , eccentric bearing e , and sleeve e' , etc., as will be seen more particularly by reference to Figs. 2 and 4.

The journal bearings b , for the idler sheave journals i' , are mounted so as to be 10 adjustable both vertically and in inclination upon pillow blocks B , by means of the screws b' , b' , while the blocks B , are themselves horizontally adjustable upon their foundations F , as by means of the screws 15 f , and nuts f' , all as shown more particularly in Fig. 1. Thus the idler sheaves I , I , are adapted to compensate fully and accurately for the difference in axial alignment between the driving pulley J , on the 20 power shaft K , and the eccentric sleeve pulley e^* , in such manner as to reduce frictional resistance to a minimum and to insure speed of rotation of the eccentric bearing e , and gyratory shaft A .

25 What I claim as my invention and desire to secure by Letters Patent is,

1. A belt drive comprising a driven pulley mounted to rotate about a vertical axis formed with one or more rope grooves, one 30 or more drive ropes engaging said pulley, a horizontal drive shaft and a power pulley thereon formed with grooves corresponding to the driven pulley engaging with said endless drive rope or ropes, guide pulleys

and shafts therefor intermediately installed 35 between said power pulley and said rotatable sleeve pulley and engaging with said endless drive ropes, and means for effecting the universal adjustment of said intermediate shafts and guide pulleys, for the purpose set forth.

2. In crushing apparatus of the character designated, in combination, a gyratory shaft suspended from above, an eccentric bearing for the lower end of said shaft mounted in 45 a rotatable sleeve, a plurally grooved pulley attached to said rotatable sleeve, a plurality of endless ropes engaging with said pulley, and means for driving said endless ropes, for the purpose described.

3. In crushing apparatus of the character designated, in combination, a gyratory shaft suspended from above, an eccentric bearing for the lower end of said shaft mounted in a rotatable sleeve, a plurally grooved pulley 55 attached to said rotatable sleeve, a plurality of endless ropes engaging said pulley, idler pulleys interposed between the power pulley and said pulley on the eccentric bearing sleeve, said power pulley, and means for adjusting said idler pulleys in inclination, for the purpose of guiding said driving ropes with accuracy as related to said eccentric sleeve pulley.
